[57] ABSTRACT

An electron gun for use in electron irradiation equipment. The gun comprises a cartridge including a Wehnelt electrode and a filament with two plug electrodes mounted on an insulating plate. The filament is mounted between the Wehnelt electrode and a conductive plate by two fasteners and can be adjustably aligned with respect to the Wehnelt electrode by moving the electrode with respect to the filament before the mounting is made fast. The electrical potential supply terminal has two jacks which receive the plug electrodes thereby mechanically and electrically coupling the cartridge to the potential supply and the Wehnelt electrode receives its potential through a resilient contact on the potential supply terminal.

FIG. I
PRIOR ART

ELECTRON GUN FOR ELECTRON IRRADIATION EQUIPMENT

BACKGROUND OF THE INVENTION

The present invention relates to an electron gun for use in electron irradiation equipment such as scanning type or transmission type electron microscopes and x-ray micro-analyzers.

Conventional electron guns of this type, which are used for electron irradiation equipment, are large in size as a result of their complex structure and thus have high manufacturing costs.

The conventional electron guns comprise an electrode assembly and a filament which are mounted separately and thus necessitate alignment of the filament and the electrode each time the electron gun is assembled.

The alignment of the filament and the electrode in the prior art electron guns is not reliable when the filament becomes heated, since the alignment is sensitive to the thermal expansion of the various parts of the electron gun.

The conventional electron guns also have the disadvantage that the connections between the power supply and the various electrodes is complicated and the voltage applied to the electrode assembly is generally through the various parts of the mounting structure.

SUMMARY OF THE INVENTION

The main object of the present invention is to solve the aforementioned problems of the conventional electron guns by providing an electron gun for use in electron irradiation equipment which has a simple construction and is small in size.

It is another object of the present invention to provide an electron gun which permits easy and positive alignment of the filament tip with respect to the main electrode.

A further object of the present invention is to provide an electron gun comprising a cartridge comprising a filament having two plug electrodes and a main electrode, where the cartridge is both mechanically and electrically detachably coupled to the supply terminal for supplying electric potential to the cartridge.

These and other objects of the invention are carried out by the electron gun comprising a cartridge comprising a filament having two plug electrodes, a main electrode and means connecting the filament to the main electrode and for aligning the filament with the main electrode. The electron gun also comprises supply terminal means for supplying electric potential to the main electrode and to the two plug electrodes and includes jack means for detachably coupling the two plug electrodes both mechanically and electrically to the supply terminal means and means separate from the jack means for detachably electrically coupling the main electrodes to the supply terminal means.

The cartridge includes an insulating plate member that has the two electrodes mounted thereon and projecting therefrom on one side thereof. At least one fastener is received through an aperture in the insulating plate member with a clearance thereabout to permit adjustable movement of the main electrode with respect to the insulating plate member thereby providing for the adjustable positioning of the main electrode with respect to the filament. The supply terminal means

has jack means that receive the two plug electrodes therein for mechanically coupling the cartridge to the supply terminal means. This means for electrically coupling the main electrode comprises a resilient contact electrically contacting the main electrode when the cartridge is mechanically coupled to the supply terminal means and means biasing the electrical contact outwardly of the supply terminal means.

Having in mind the above and other objects that will be obvious from an understanding of the disclosure, the present invention comprises a combination and arrangement of parts illustrated in the presently preferred embodiments of the invention which are hereinafter set forth in sufficient detail to enable those persons skilled in the art to clearly understand the function, operation, construction and advantages of it when read in conjunction with the accompanying drawings.

BRIEF DESCRIPTION OF THE DRAWINGS

FIG. 1 is a sectional view of a conventional electron gun for use in electron irradiation equipment.

FIG. 2 is a sectional view of an electron gun for use in electron irradiation equipment according to the present invention.

DETAILED DESCRIPTION OF THE INVENTION

FIG. 1 shows an example of a conventional electron gun for use in electron irradiation equipment in which a pair of electrodes 2, are attached to a filament 1 by spot welding. The electrodes 2, are fixed to an insulating plate 3 and connected to a pair of terminals 6 on an insulating block 5 by an intermediate conductor member 4.

The middle portion of a metal cylinder 7 holds insulating block 5, in an adjustable position which may be varied by use of an adjusting screw 5a. The lower portion of cylinder 7 has a Wehnelt electrode 8 screw-mounted thereon. The electrode 8 has a small hole 8a through which electron beams pass. The upper portion of the cylinder 7 has a flange 7a on which a fastening ring 9 is rotatably fitted for connecting the assembly to the remaining structure.

A metal fitting 12 is fluidtightly fixed through a seal 11 to a flange 10a formed at the lower end of an electron gun insulator 10. The upper end portion of ring 9 has an internal thread which engages an external thread of a portion of the lower end of metal fitting 12, so that turning the ring 9 fastens the upper flange 7a of said cylinder 7 to the lower end of the metal fitting 12.

When so fastened, an elastic metal tongue 6a, which is attached to the upper portion of each terminal 6, is pressed against terminal 14 which is fitted through an insulating material 13 in such a manner as to seal the central opening in the metal fitting 12. The terminal 14 is connected to a power source (not shown).

The metal fitting 12 is connected to a voltage supply (not shown) by wire 15 for applying the voltage to the Wehnelt electrode 8. The voltage is applied to the Wehnelt electrode 8 through said metal cylinder 7.

One disadvantage of the electron gun, as described above, is that the insulating block 5 is adjusted by the adjusting screw 5a prior to use of the electron gun, and the tip of the filament 1 is thereby aligned to the small hole 8a in the Wehnelt electrode 8. In spite of the preliminary adjustment, when the filament 1 becomes heated after energization, the metal cylinder 7 under-

goes thermal expansion thereby varying the alignment between the filament tip and the hole 8a.

In addition since the electron gun has a complicated structure and is costly, when the filament 1 has been consumed, a block comprising the filament 1, electrodes 2 and insulating plate 3 must be replaced by removing the Wehnelt electrode 8. This necessitates another alignment of the tip of the filament 1 and the small hole 8a in the Wehnelt electrode for each replacement.

A further disadvantage of the conventional electron gun, as described with reference to FIG. 1, is that voltage from the power source is applied to the Wehnelt electrode 8 through the electric wire 15, metal fitting 12, ring 9 and the metal cylinder 7. This contributes to complexity of construction of the electron gun.

An embodiment of the electron gun according to the invention will now be described by reference to FIG. 2. FIG. 2 is a sectional view of the electron gun, in which both ends of a V-shaped filament 21 are fixed by spot welding to the lower ends of a pair of plug or bar electrodes 22 which pass through and are sealed in by glass to an insulating plate 23 composed of steatite or other similar material. Insulating plate 23 may be made of mica, and the electrodes 22 may be fastened thereto by nuts. The insulating plate 23 corresponds to insulating plate 3 of the prior art electron gun described before.

A Wehnelt electrode 24 has a small hole 24a at the center thereof to pass electron beams through and has a portion or flange surface of the insulating plate 23 or the filament side thereof. The insulating plate 23 is held between the Wehnelt electrode 24 and a conductive metal doubling plate 25 fastened together by a clamping bolt 26. The clamping bolt 26 screws into a tapped hole 25a in the doubling plate 25 through a hole in the flange of the Wehnelt electrode 24 and a clearance hole 23a in the insulating plate 23. By fastening the clamping bolt 26, the Wehnelt electrode 24 can be fixed in close contact with the insulating plate 23.

When fastening the clamping bolt 26, the position of the Wehnelt electrode 24 with respect to the insulating plate 23 can be adjusted by utilizing the clearance hole 23a in the insulating plate 23. By this means, alignment of the tip 21a of the filament 21 and the small hole 24a in the Wehnelt electrode can be effected.

Each filament electrode 22 passes through the insulating plate 23, and through a hole 25b without coming in contact with the doubling plate 25, and forms a projected end 22a on the side of the insulating plate 23 opposite the filament 21. The projected ends are detachably coupled as plugs in jack 28 fixed to an electron gun insulator 27. Thus when electrodes 22a are received in jack 28, the filament is both electrically and mechanically coupled thereto.

A Wehnelt terminal 29 has a specified voltage applied thereto and is fixed to the electron gun insulator 27. Terminal 29 has a spring contact 30 attached to the lower end thereof which resiliently presses against the metal doubling plate 25. This means that the specified voltage is applied from the Wehnelt terminal 29 to the Wehnelt electrode 24 through said spring contact 30, metal doubling plate 25 and clamping bolt 26.

During operation of the electron gun in electron irradiation equipment such as scanning type electron microscopes, the inside of the electron gun insulator 27

is kept at atmospheric pressure and the filament 21 is in a vacuum.

For example, in a small scanning type electronic microscope 3 volts of voltage is applied and 2 amperes of current flows between the electrodes 22 connected to the filament 21. Under this condition, thermoelectrons produced at the filament 21 are controlled by the Wehnelt electrode 24 with a potential difference of, for example, of some 500 volts lower than the filament potential. The electrons are accelerated and induced through the small hole 24a toward an anode (not shown) which has a potential difference of, for example, some 10 kilovolts higher than the filament potential.

15 During maintenance of the electron gun, in which there is an inspection or adjustment made, the filament 21 is put at atmospheric pressure, and the projected ends 22a of the electrodes 22 are pulled out of the jack 28. The removed assembly defines a cartridge C, which 20 comprises the filament 21, electrodes 22, insulating plate 23, doubling plate 25 and Wehnelt electrode 24. The cartridge C is integrally and easily detachable 25 from the apparatus proper. In addition it is mechanically coupled to the apparatus by the filament electrodes in contrast to conventional electron guns.

Before inserting cartridge C into jack 28, the filament tip 21a and the small hole 24a in the Wehnelt electrode can be preliminarily aligned with each other by adjusting the position of the Wehnelt electrode 24 with respect to the insulating plate 23, as described before. In addition, the cartridge is small, of simple construction, and manufacturable at low cost, which means that the whole cartridge C can be easily changed for the purpose of a filament change.

35 To prevent the adhesion of metallic vapor from the filament 21 on the entire surface of the insulating plate 23 during use, thus causing short circuits between the filament electrodes 22 or between the electrodes 22 and the Wehnelt electrode 24, it is desirable to provide 40 each electrode 22 with a flange 22b, which is spaced from the insulating plate 23, or to provide an indented groove 24b along the internal base portion of the Wehnelt electrode 24 which comes in contact with the insulating plate 23. This increases the durability of the cartridge C by increasing the surface distance between the electrodes 22 and the electrode 24.

The present invention permits a remarkable reduction in size of the Wehnelt electrode and also maintains alignment of the filament and the Wehnelt electrode 50 even when the filament becomes heated.

As a result of said marked size reduction of the Wehnelt electrode, the Wehnelt electrode, filament electrodes and supporting insulating plate can be manufactured at low cost in an integral cartridge which is replaceable as a whole when the filament must be replaced. Therefore, by aligning the Wehnelt electrode and the filament beforehand, when the cartridge is manufactured, the replacement of the filament is comparitatively easy.

60 In addition, as a result of the use of a pair of electrodes with the spot-welded filament inserted in jacks on the electron gun insulator, the whole electron gun has a more simplified construction and can be made smaller in size than conventional electron guns. This, for example, permits the manufacture of bench scanning type electron microscopes which are easy to carry and install.

While preferred embodiments of the invention have been shown by way of example in the drawing, it will be understood that the invention is in no way limited to these embodiments.

What we claim is:

1. An electron gun for use in electron irradiation equipment, said electron gun comprising: a cartridge comprising a filament having two plug terminals receptive of an electric potential applied thereto during use, a main electrode receptive of an electric potential applied thereto during use for focusing electrons emitted by said filament, and mounting means having a major surface, said filament and said main electrode being disposed on said major surface and relatively positioned to effect focusing by said main electrode of the electrons emitted by said filament; and means for removably mounting said cartridge including supply terminal means for supplying electric potential to said main electrode and said two plug terminals including jack means for detachably coupling said two plug terminals both mechanically and electrically to said supply terminal means and means separate from said jack means for detachably, electrically coupling said main electrode to said supply terminal means whereby said cartridge may be detached from said mounting means.

2. An electron gun according to claim 1, wherein said cartridge includes an electrically insulating plate member and means mounting said two plug terminals on said insulating plate member projecting therefrom on at least one side thereof, said main electrode having a planar base portion, an electrically conductive plate member having means therein defining two openings therethrough alignable with said two plug terminals and having a greater cross-sectional area than said two plug terminals to define a clearance thereabout, and mounting means mounting said insulating plate member between said base portion of said main electrode and said conductive plate member disposing said one side of said insulating plate member facing said conductive plate member and aligning said two plug terminals with

said two openings and for electrically connecting said base portion to said conductive plate member.

3. An electron gun according to claim 2, wherein said mounting means comprises means defining a first pair 5 of apertures in said base portion of said main electrode, means defining a second pair of apertures in said insulating plate member aligned with said first pair of apertures, means defining a third pair of apertures in said conductive plate member aligned with said second pair 10 of apertures and having internal threads, and two threaded fasteners receivable in the three pairs of apertures to fasten said main electrode to said insulating and conductive plate members.

4. An electron gun according to claim 3, wherein said 15 means defining said second pair of apertures comprising means defining a clearance about each of said fasteners to permit adjustable movement of said main electrode with respect to said insulating plate member thereby providing for the adjustable positioning of said main electrode with respect to said filament.

5. An electron gun according to claim 1, wherein said 20 means for connecting comprises means for adjustably positioning said main electrode with respect to said filament.

6. An electron gun according to claim 1, wherein said 25 main electrode comprises a Wehnelt electrode.

7. An electron gun according to claim 2, wherein said 30 base portion has means therein defining a groove at the end portion thereof facing said two plug electrodes and contacting said insulating plate member to increase the surface distance between said two plug electrodes and said base portion.

8. An electron gun according to claim 1, wherein said 35 means for detachably coupling said main electrode comprises a resilient contact electrically contacting said main electrode when said cartridge is mechanically coupled to said supply terminal means and means biasing said contact outwardly of said supply terminal means.
